UNITED STATES PATENT OFFICE.

NATHAN COLE BUTLER AND FRANK D. ROSENBERGER, OF LEIPSIC, OHIO.

AUTOMATIC HEAT-REGULATING DEVICE.

SPECIFICATION forming part of Letters Patent No. 400,826, dated April 2, 1889.

Application filed May 7, 1888. Serial No. 273,069. (No model.)

To all whom it may concern:

Be it known that we, NATHAN COLE BUTLER and FRANK D. ROSENBERGER, residents of Leipsic, in the county of Putnam and State 5 of Ohio, have invented certain new and useful Improvements in Automatic Heat-Regulating Devices; and we do hereby declare that the following is a full, clear and exact description of the invention, which will enable others skilled in the art to which it 10 pertains to make and use the same:

This invention relates to automatic heat-regulating devices.

The object is to produce a device for regulating automatically the flow of gas to a stove using the same as fuel, whereby an even temperature may be at all times maintained in a room in which the stove is placed; furthermore, to produce a device which shall be 15 simple of construction, efficient and durable in use, and comparatively inexpensive of production.

With these objects in view the invention consists in the improved construction and 20 combination of parts of an automatic heat-regulating device, as will be hereinafter fully described in the specification, illustrated in the drawing, and more particularly pointed out in the claims.

30 In the accompanying drawing, forming part of this specification, and in which like letters of reference indicate corresponding parts, the figure is a side elevation, partly in section, showing the device intact.

35 Referring to the drawing, A designates a frame, which is to be fastened to the wall of a room in a perpendicular position, and at a part subject to the greatest change of temperature—as, for instance, near the door. To 40 this frame is secured, at its upper end, a thermostat, B, of the ordinary construction, and composed of a composition of metals that will be highly sensitive to the different changes of the atmosphere. The lower portion, b, of the 45 thermostat connects with a valve-stem, D, which passes through a stuffing-box, d, and into the globe-valve E. The lower end of the valve-stem is provided with shoulders d', which engage corresponding shoulders, f, on 50 the cap f', which is screwed on the valve F.

Between the end of the valve-stem and the top of the valve a space is left, in which is

placed a rubber gasket, f², the peculiar function of which will be described farther on.

G designates the branch pipe leading from 55 the supply-pipe to the burner. This pipe has a globe-valve mounted on it provided with a gravity-valve, g, which is held or poised above the valve-seat g' by the pressure of the gas, and to insure its perfect working—that is, to 60 cause the valve to set squarely on its seat—the valve-stem works in an opening, g², in the cap of the valve, thereby causing the parts to come together to form a gas-tight joint. This branch pipe is further provided with a mixing-chamber, H, having air-inlets h, through 65 which the air is fed to the gas in sufficient quantities to insure the complete combustion of all the carbon in the gas, which not only serves to produce a more intense heat, but 70 also to prevent the interior of the stove from becoming fouled with lamp-black. The gas-pipe h' extends some distance into the branch pipe, so as to prevent any of the gas escaping 75 from the inlets.

I designates a smaller pipe leading from the branch pipe G, and designed to supply gas to the stove when the pressure in the globe-valve has become insufficient to hold the gravity-valve up, by means of which a 80 small amount of gas may at all times be fed to the stove.

The device operates as follows: Suppose it is desired to keep the temperature of a room at 70°. The valve F on the thermostat is first 85 raised above its seat a sufficient distance to allow the necessary quantity of gas to pass to the burner to raise the temperature of the room to that degree, and the thermostat is then secured in place and holds the valve fixed 90 in the position to which it was adjusted; but should the weather moderate the temperature in the room would naturally rise above the 70°. Should this happen, the difference in temperature would immediately act on the 95 thermostat and cause it to expand, thereby closing the valve slightly and cutting off enough of the gas to cause the temperature to remain at the desired degree. Now if the temperature of the room should become lower 100 than 70° the thermostat would contract, thereby opening the valve and allowing a larger supply of gas to be fed to the stove; but should the temperature of the room rise to a

point greatly above that originally intended the thermostat would expand more than would be necessary to close the valve, and in that event the valve-stem would press upon the 5 rubber gasket, thus preventing injury to the mechanism, as by the jamming of the parts together. The flow of gas would then be cut off from the branch pipe through the valve, but would still be fed in a small quantity to the 10 branch pipe through an opening, *e*, in the diaphragm of the valve. The pressure of gas in the branch pipe would then be insufficient to poised the gravity-valve. This would then close and cause the gas to be fed through the 15 small pipe *I*.

Having thus fully described our invention, what we claim as new, and desire to secure by Letters Patent, is—

1. In an automatic heat-regulating device, 20 the combination of a main burner, a supply- pipe communicating therewith, a branch pipe communicating with the supply-pipe, a supplemental burner located adjacent to the main burner and communicating with the branch 25 pipe, a gravity-valve in the main pipe between the branch pipe and main burner open-

ing toward the burner, and a globe-valve in the supply-pipe having a permanently-open perforation in the diaphragm, substantially as described. 30

2. In an automatic heat-regulating device, the combination of a main burner, a supply- pipe communicating therewith, a branch pipe communicating with the supply-pipe, a supplemental burner located adjacent to the main 35 burner and communicating with the branch pipe, a gravity-valve in the main pipe between the branch pipe and main burner opening toward the burner, a globe-valve in the supply-pipe having a permanently-open perforation in the diaphragm, and a thermostat 40 connected to said valve, substantially as described.

In testimony that we claim the foregoing as our own we have hereunto affixed our signatures in presence of two witnesses. 45
